3 Claims. (Cl. 200—117)

1

This invention relates to electrical protective devices and more particularly to circuit interrupters of the open fuse type for power transmission.

An object of this invention is the provision of a simple and practical open fuse cutout for an electric power transmission line, the cutout being well suited for conducting the line current in an efficient manner within load limits and for reliably opening the line upon encountering an overload current.

Another object of this invention is that of providing a strong and efficient open fuse cutout which affords physically stable support for the fuse link thereof and reliably gives a continuous current path, yet promptly and positively opens the current path when current limits are exceeded.

A further object of this invention is the provision of an inexpensive and practical open fuse cutout such as may be installed on power transmission line poles, towers, transformers, or the like.

A still further object of this invention is that of providing an open fuse cutout in which the fuse link thereof is reliably supported in tension and is effectively electrically connected.

Another object of this invention is the provision of a strong and mechanically simple open fuse cutout which rigidly retains a circuit protective setting corresponding to normal current conditions and promptly snaps to circuit interrupting position upon encountering a current overload.

As conducive to a clearer understanding of certain features of the present invention, it may be noted at this point that open fuse cutouts are intended to arrest the flow of current by spending a fusible electrically conductive or heat sensitive portion in response to overload current and thereupon open a related electrical line with a snap action. A variety of these cutouts employ contact arms which support the fuse and are electrically connected into the transmission line to form an electrically conductive portion thereof. In these cutouts the contact arms are biased in favor of pulling the leads of the fuse apart when fusion occurs, thus to achieve a further opening of the transmission line and decrease the danger of arcing. To restore the cut-

2

out to electrically conductive condition relative to the power line, a replacement fuse of desired rating is inserted between the contact arms, and is supported in tension by the same until current overload releases the bias in favor of separation once more.

These electrical protective devices have come into demand in such important fields as the outdoor transmission of electrical power, and are often used on line towers, poles, transformers, or the like, thus to afford a component part of the power transmission system. Among these systems are those employed for rural electrification, which are mentioned here as an example illustrating certain conditions and economic levels of use. Thus, it will be appreciated that economy is a highly important factor in many installations where the demand exists for open fuse cutouts, considering too that the quantity of cutouts needed in a particular system or for an over-all plan for electrification, may be quite large.

A number of the heretofore known circuit interrupters or open fuse cutouts have been eliminated from possible use for any of a variety of their intended purposes by virtue of such considerations as failure to lend themselves readily to mass production techniques and yet give a strong, easily assembled, reliable product. More specifically, some of these cutouts have been particularly objectionable from the standpoint of being highly expensive to produce on the competitive market. There are others which, once installed, offer an extremely unfavorable aspect of upkeep.

In this connection, it will be appreciated too that certain open fuse cutouts in the prior art are physically too weak because the precise character and arrangement of parts, or otherwise, they are very difficult to reset or service from a safe distance, as with a suitable tool, to replace a spent fuse.

Many of the heretofore known open fuse cutouts introduce a highly objectionable detriment to operating efficiency of the related electrical transmission line under normal current conditions. This fault often arises because of the very structural nature of the cutout contact arms and because small physical cross-sections exist at crucial points where the line current has to pass. Also, when attempts are made to overcome the

detrimental effect of low current capacity, the necessary changes in the cutout structure often introduce production difficulties, such as reflected by expense of the product, or are not feasible at all.

A further object of this invention, accordingly, is the provision of a practical and reliable open fuse cutout which is easy to produce and simple to service and maintain.

A still further object of the present invention is that of providing a fuse cutout of the type described, which is strong and easy to assemble and has favorable current capacity under power transmitting conditions.

The preceding objects and other objects of this invention will become more apparent upon consideration of the following description of a preferred embodiment thereof, when taken in connection with the attached drawing, in which:

Figure 1 represents, in side elevation, an open fuse cutout having features in accordance with the invention;

Figure 2 is a fragmentary view, in plan, showing details of a contact arm hinge or pivot in the apparatus depicted in Figure 1;

Figure 3 is a view in side elevation of that portion of the apparatus shown in Figure 2; and

Figure 4 is a fragmentary view, in plan, of the outer end of one of the contact arms of the open fuse cutout apparatus just mentioned.

In the particular embodiment of the present invention disclosed in the accompanying drawing, there is provided an open fuse cutout 10 which includes an electrical insulator 11 and relatively movable contact arms 12 and 13 supporting a fuse link 14 which electrically interconnects these arms. The cutout 10 further comprises line terminals 16 and 17 individually corresponding to the contact arms 12 and 13 for connection of the cutout into a power line of an electrical transmission system. Terminals 16 and 17 are in electrically conductive relation with each other through the fuse link 14 and a fusible portion 34 of the latter, so long as the link remains conductive. The relatively movable contact arms 12 and 13 serve to impose tension on the fuse link 14 and to separate the free ends of the fusible portion 34 when this is melted or softened by heat of overload current in the power transmission line. For this purpose, the contact arm 12 is pivoted and biased in an unique manner which will be explained more fully hereinafter. Contact arm 13 preferably is substantially fixed in position.

In shape, the insulator 11 illustratively is oblong, as for mounting with the major dimension in upright position, and conveniently is round or substantially circular in transverse section. It is made of porcelain, glass, or of any other suitable dielectric. The long dimension of the insulator advantageously gives more available length for spacing the terminals 16 and 17, considering that an effective spacing is desired to keep the electrical transmission line open after the fuse link is expended due to overload current.

A bracket 25 illustratively serves for mounting the insulator 11 as in an upright position on a pole, line tower or transformer casing, and preferably is disposed at some point in the general vicinity of midlength of the insulator body; for example, at about half way between the terminals 16 and 17. The inner end of the bracket 25 preferably is of a form which connects to only one side of the transverse periphery of the insulator body, this connection for example being on

the side opposite from those portions of the open fuse cutout 10 which are electrically conductive in the power transmission line. The bracket 25 illustratively is in the form of a metal strap or flat bar extending transversely from one side of the insulator 11 and having one or more openings 25a therethrough, clear of the insulator body for receiving a screw, bolt, or the like to support the cutout 10 in useful position. The inner end of the strap conveniently is affixed to the insulator 11 by being embedded therein or seated in a transverse opening in the side of the insulator body and cemented in the seated position. It will, of course, be understood that a conventional collar or band of metal is at times employed to encircle the insulator body and thus affix the bracket, but this arrangement preferably is avoided for such reasons as often being susceptible to easy connection with the line to ground, as by birds roosting on the cutout 10. By keeping the bracket 25 to one side of the insulator body and disposing the contact arms 12 and 13 on the opposite side so as to be remote from this bracket, danger of line to ground connection between the several elements is considerably reduced.

The contact arms 12 and 13 illustratively have supports 18 and 19, for respectively mounting the same to opposite end portions 11b and 11c of the insulator 11. The support 18 preferably is a strap or a flat bar fixed at one end to the side of lower end portion 11b as by being embedded therein or seated in a transverse opening in the insulator body and cemented in position. It is made of electrically conductive material such as copper-clad steel or a copper alloy such as of cobalt-beryllium-copper composition and affords a fixed terminal 16 of the contact arm 12 for receiving an electrical lead for power supply. From the insulator end portion 11b, the strap of support 18 extends outward as on a sharp, straight-away longitudinal curve to a substantially parallel outer end position relative to the longitudinal axis of the insulator 11. The shape of the strap may for example be that of a substantially right-angle piece having a leg 18b transverse to the longitudinal axis of the insulator 11 and a leg 18c substantially parallel to the axis. There is a longitudinal slot 18a through the curved strap portion of support 18 and following around the bend of the curve to points short of the respective ends of the strap. The outer end of the support 18 conveniently has an opening 18d for receiving terminal 16 which illustratively includes a nut and bolt for clamping an electrical lead to conductive position relative to the strap end and contact arm 12. If desired, this terminal may be integral with support 18 as by welding. Welding preferably is employed for increased electrical capacity of the cutout 10.

Support 19 for the contact arm 13 conveniently may be of the same strap material as support 18. In this instance, however, the support 19 conveniently is a substantially straight piece having its inner end affixed to end portion 11c of the insulator 11 such as by embedding or inserting into a transverse opening in the side of the insulator body and cemented in place. This support for the contact arm 13 then extends transversely from the insulator side wall and terminates some distance out from the point of anchoring. Usually, the supports 18 and 19 are affixed to opposite ends of the insulator 11 and on the side of the body thereof opposite from the side where

the bracket 25 is disposed. The contact arms 12 and 13 advantageously extend from their respective supports in a generally opposite direction from the bracket 25 so as to be remote from the latter.

Contact arm 12 preferably is made of a substantially rigid strap or flat bar, this of electrically conductive material such as copper-clad steel or copper alloy. A cobalt-beryllium-copper alloy is quite satisfactory for the strap composition. The contact arm strap advantageously has two opposed transverse notches 12a and 12b entering the opposite narrow edges thereof just short of the inner end and extending toward the longitudinal axis of the strap material, thus leaving a reduced section 12c slightly narrower across than the width of the slot 18a for the strap to fit in movable relation within the latter and yet receive lateral bracing by the adjacent portions of the support 18. Notches 12a and 12b are wide enough to clear the thickness of support 18 and also preferably are deep enough to receive the adjacent walls of support 18 when the inner end of arm 12 is inserted in the slot 18a and is subsequently rotated about its longitudinal axis. This allows easy assembly of the contact arm 12 to pivotal relation with its support. In the assembled condition, the contact arm advantageously has the long dimension of its transverse cross-section substantially lateral to the fuse link for rigidity and ease of replacement of the link. The same holds true for the lateral cross-section of the contact arm support 18.

The notched construction of the inner end of contact arm 12 thus enables pivotal movement of this arm relative to the support 18. Further, by making the slot 18a of the support sufficiently long, the contact arm 12 is easily mounted to the pivotal position. The lower end of the slot 18a, as in the vertical leg 18c, conveniently affords a rest or pivotal bearing for the reduced section 12c of the arm. Also, the width of the notches 12a and 12b as measured longitudinally of the contact arm 12, and the proportionate thickness of the support 18 in these notches conveniently impose a control over the extent of lowering the arm to a point of binding and stopping. As an alternative, the length of the contact arm 12 behind the notches 12a and 12b illustratively is sufficient to contact the underneath side of support 18 and thus impose a lower limit on movement of this arm. In this, the notches are effective to arrest longitudinal movement of the contact arm.

The pivoted contact arm 12 is biased by means of a spring 20 so as to be urged to swing away from the contact arm 13 and accordingly increase the separation of the outer ends of these arms. The spring 20 illustratively is a torsion spring as of the spiral wire variety welded at its inner end to the contact arm support 18, and bearing at its outer end on contact arm 12. Spring 20 is made of an electrically conductive material, as for example a resilient copper alloy.

Thus, by employing an electrically conductive biasing spring, the pivotal connection between contact arm 12 and the arm support 18 is reliably shunted to assure better conductivity in the cutout 10 and greater electrical capacity in the vicinity of the pivot point.

The outer end of contact arm 12 conveniently is longitudinally split and the resulting portions turned or bent back to give integral hooks 12d and 12e on opposite sides thereof for holding the fuse link 14. These hooks are made, for example,

of the same strap material as contact arm 12 and in being integral with the strap body, afford a highly satisfactory electrical path. Each of the hooks (Figure 4) preferably extends backward and diverges away from the main body of contact arm 12, thus forming an angle for effectively receiving and holding an end of fuse link 14. An outer portion 12f of contact arm 12 and including these hooks, conveniently is inclined from the plane of a rearward portion 12g, toward the outer end of contact arm 13 so as to enhance the receiving and holding effect of the hooks. The several hooks advantageously are in substantially the same plane as the adjacent portion 12f of arm 12.

The contact arm 13 preferably is fixed to its corresponding support 19, as by riveting, welding or both. This contact arm, for example, also is made of electrically conductive strap material such as copper-clad steel or cobalt-beryllium-copper alloy. At the inner end the strap is bent away so as to extend substantially vertically above the support 19 and there conveniently has an opening 13a for receiving the corresponding terminal 17 of the power line in which the cutout 10 is to serve. This terminal may be made integral with the corresponding contact arm 13 as by welding to increase the electrical capacity of the cutout 10. At the outer end, the arm 13 is provided with means for receiving and holding the fuse link 14, such as hooks 13d (not shown) and 13e on portion 13f which is inclined from the plane of a rearward portion 13g, toward the outer end of contact arm 12, thus to enhance the receiving and holding of fuse link 14. Arm 13 preferably has the long dimension of its transverse cross-section substantially lateral to the link 14 for rigidity, and ease of replacement of the link. The same holds true for the lateral cross-section of arm support 19.

Fuse link 14 preferably includes an opposed pair of electrical conductors 32, made, for example, of copper wire, and which are provided at their outer ends with eyes 33. The inner end portions of the electrical conductors 32 are spaced apart to form a gap and located in this gap and connected to the conductors 32 is the fusible element 34 of relatively low melting point material. This fusible element 34 and the inner ends of conductors 32 preferably are enclosed within a tube 35 made, for example, of a weather-protective material such as phenolic resin lined with fiber capable of emitting an arc-suppressing gas due to proximity with the electric arc formed coincident with rupture of the fusible element 34 on overload current. The conductors 32 conveniently have stops 29, which for example are electrically conductive washers, affixed thereto between the inner sides of eyes 33 and the ends of tube 35 as by welding or soldering.

In use of the cutout 10, one of the opposed electrical conductors 32 of the fusible link 14 is set into the hook 12d or 12e with the corresponding stop 29 on that side of the contact arm 12 which is remote from arm 13. For this, a conventional switch stick is useful to handle an appropriate one of the eyes 33. With further use of the switch stick or tool, conductor 32 at the opposite end of the link 14 is set into either hook 13d or 13e of fixed contact arm 13 with the corresponding stop 29 outside this arm. In this latter operation, the pivoted contact arm is pulled toward fixed arm 13, against the bias of spring 20. Stops 29 then engage the contact arms 12 and 13 while the link 14 is in tension under the

bias of arm 12. The outer portions 12f and 13f of the contact arms, in being inclined and substantially approaching each other, advantageously maintain the bottoms of the hooks 12d and 12e substantially toward the bottoms of the opposed hooks 13d and 13e for positively receiving and holding the fuse link in the bight portions of the hooks. It should also be noted that while parts of conductors 32 may engage contact arms 12 and 13, stops 29 will engage these respective arms at one point to achieve limited area contacts under pressure due to spring 20. Then with normal current conditions prevailing, the open fuse cutout 10 serves to maintain current flow through the transmission line of which terminal 16, inclusive of support 18, the shunt spring 20, contact arm 12, fusible link 14, contact arm 13 and terminal 17 comprise a part. If, however, overload currents pass through the electrically conductive portions just named, the fusible component 34 in the link 14 ruptures. When that occurs, contact arm 12 pivots (clockwise in Figure 1) with a snap under the force of spring 20, quickly pulling apart the electrical conductors 32 of link 14. Current flow thus no longer prevails across the cutout 10, but can be restored, if safe transmission limits exist, by introducing another link 14 having a fusible component 34 of appropriate current rating.

Where, for example, the cutout 10 is to be used for lending safety to a high voltage electrical transmission line, as is often the case, a considerable benefit is had by employing an insulator 11 having a corrugated surface, such as a surface provided by a series of raised annular portions 11a spaced along the length of the insulator body. This corrugated surface is illustratively achieved by molding the insulator to form inclusive of the corrugations, such as by pouring a desired dielectric composition into a mold having sufficient dimensions to produce the entire insulator unit as a molded product. The corrugated surface tends to arrest discharge between the terminals 16 and 17 by increasing the creepage distance therebetween. The mounting bracket 25 conveniently is secured to the insulator 11 at a point intermediate the plurality of raised annular portions 11a which then also protect this element against discharge. When desired, the several end portions 11b and 11c of the insulator 11, and also the intermediate portion where bracket 25 is affixed, may be made substantially cylindrical in shape and in axial alignment. Also, if desired, the several raised annular portions 11a may be disposed between the cylindrical portions of the insulator and in axial alignment with these portions by integral relation achieved by molding the insulator body.

To further assist in the avoidance of free electrical discharge over the surface of the insulator 11, as where the insulator is to be used in the upright position, the bottom surface of at least some of the raised annular portions 11a preferably is substantially normal to the longitudinal axis of the insulator or is inclined in upward direction from the rim of the corresponding annular portion. The top surface of at least some of the raised annular portions 11a advantageously slopes downward and outward from a sheltered position beneath the underneath surface of the annular portion 11a next above or from an undercut position relative to the top or intermediate cylindrical portion of the insulator, thus being protected against moisture.

Thus, it will be seen that in this invention there

10
15
20
25
30
35

45

is provided an open fuse cutout in which the various objects noted herein, together with many thoroughly practical advantages, are successfully achieved. It will be seen that the cutout is simple and efficient and is effectively biased in favor of snapping to open circuit position upon overload currents being encountered. Further, it will be seen that the cutout not only is effectively biased for achieving open circuit conditions upon overload, but very efficiently avoids sacrifice of electrical capacity in the vicinity of the pivoting means should normal current conditions prevail. Then, too, it will be appreciated that the cutout is highly effective and conducive to safe electrical conditions.

The features relating to the structural mounting arrangement for the insulator 11 are set out and claimed in U. S. patent application filed June 10, 1949, by James M. Wallace and Earl F. Beach, Serial No. 98,378, and assigned to the assignee of the instant application.

Having described a preferred embodiment of the invention in accordance with the patent statutes, it is desired that the invention be not limited to this particular structure, inasmuch as it will be obvious to persons skilled in the art that many modifications and changes may be made in this particular structure without departing from the broad spirit and scope of this invention.

We claim as our invention:

1. An open fuse cutout comprising an electrical insulator, spaced electrically conductive contact arms mounted on said insulator and being bent to substantially approach each other toward their outer ends to maintain the bottoms of opposed integral hooks at the outer ends thereof inward for positively receiving and holding a fuse link, one of said arms being substantially fixed in position on the insulator, a terminal fixed on the insulator for the other arm, and said other arm being movably mounted at its inner end relative to said terminal for swinging away from the substantially fixed arm, and a spring urging movement of the latter arm away from said substantially fixed arm.

2. An open fuse cutout comprising an electrical insulator, an electrically conductive contact arm mounted on said insulator and having a substantially fixed position throughout, an electrically conductive support connected to said insulator away from said substantially fixed contact arm and having an elongated slot therein and a terminal on the body thereof, a movable electrically conductive contact arm of strip form having at least one edge at the inner end thereof notched for receiving a side wall of said slot when the greatest cross-sectional dimension of the arm is substantially transverse of said slot and with said movable arm in pivotal engagement with an end of said slot to form a pivot with the same for swinging away from said substantially fixed contact arm, both of said arms being directed outward from said insulator, and a spring urging movement of the movable arm away from said substantially fixed arm while biasing it into engagement with said end wall of the slot.

3. An open fuse cutout comprising an electrical insulator, an electrically conductive contact arm mounted on said insulator and having a substantially fixed position throughout, an electrically conductive support connected to said insulator away from said substantially fixed contact arm and having an elongated slot therein and a terminal on the body thereof, a movable electrically conductive contact arm of strip form
